CRACKING HYDROCARBON OIL

William Edward Lemen, Chicago, Ill., assignor to
 Universal Oil Products Company, Chicago, Ill.,
 a corporation of Delaware

Application April 6, 1940, Serial No. 328,166

4 Claims. (Cl. 196—52)

This invention relates to a process for converting hydrocarbon oils containing substantially no gasoline into motor fuels of high anti-knock value. More specifically the process relates to an improved method for cracking petroleum oils and similar charging stocks in the presence of a powdered cracking catalyst.

In one specific embodiment the present invention comprises a process for converting hydrocarbon oil containing substantially no material boiling in the gasoline range which consists in separating said hydrocarbon oil into higher and lower boiling fractions, treating said higher boiling fractions with a powdered cracking catalyst under catalytic cracking conditions of temperature and pressure, heating said lower boiling fraction under cracking conditions of temperature and pressure in the absence of cracking catalyst, passing the higher and lower boiling fractions to a reaction zone, removing vaporous products therefrom to a fractionating zone, passing liquid reaction products containing catalyst in suspension to a vaporizing zone, passing the vaporous reaction products therefrom to said fractionating zone, recovering the spent catalyst from said vaporizing zone, separating gasoline and gas from said fractionating zone, mixing a higher boiling fraction of insufficiently converted oil with powdered catalyst, heating the mixture and passing it to said reaction zone for further conversion as previously indicated, heating a lower boiling fraction in the absence of catalyst and supplying it for conversion as previously mentioned.

The process is illustrated diagrammatically in the accompanying drawing which should not be interpreted as limiting it to the exact apparatus or conditions shown therein. The apparatus is shown in side elevation and has not been drawn to scale, nor has any attempt been made to proportionate the various parts of the equipment exactly.

A charging stock which may comprise crude oil or topped crude oil, but is preferably a distillate fraction of a crude hydrocarbon oil, is introduced through line 1, valve 2, pump 3, valve 4 and line 5 to fractionator 6. If a crude oil containing substantial quantities of gasoline is used, the gasoline, together with the cracked gasoline and gases produced as hereinafter described, is removed through line 7, valve 8, condenser 9 to receiver 10 from which gases are removed to suitable absorption equipment not shown through line 11 and valve 12. The gasoline may be removed to a stabilizer not shown through line 13 and valve

14. An intermediate boiling fraction is removed from the fractionator through line 15, valve 16, pump 17 and valve 18 to coil 19 which is disposed in heater 20. This oil may be heated to a cracking temperature within the range of approximately 800—1200° F. and passed through line 21 and valve 22 to reaction chamber 24. A higher boiling fraction of oil is removed from fractionator 6 through line 25, valve 26, pump 27 and valve 28 and is mixed with powdered cracking catalyst from catalyst charger 29, the catalyst entering through line 30, valve 31, pump 32 and valve 33, joining with line 25. The catalyst may be suspended in a portion or all of the charging stock or in an intermediate boiling fraction of hydrocarbon oil. The mixture of the higher boiling fraction of charging stock and catalyst passes through line 34 and valve 35 to coil 36 which is disposed in heater 37. The mixture is heated to a cracking temperature and pressure, the temperature being below that at which the cracking reaction becomes excessively rapid, usually within the range of approximately 500—1000° F. and a pressure of approximately 50—1000 pounds per square inch. The additional heat required is supplied by the intermediate boiling fraction from line 21. The reaction mixture passes through line 38 and valve 39 and thence to reaction chamber 24. A liquid level may be maintained in the reaction chamber which is operated at a temperature within the range of approximately 500—1000° F. or higher and a pressure of 100—1000 pounds per square inch. The maintenance of a liquid level in the reaction chamber permits adequate contact of the hydrocarbon oil with the powdered catalyst. The reaction products are introduced at a point below the surface of the liquid which prevents the catalyst from settling from the oil while in the chamber.

The particular advantage of this operation is that additional heat may be supplied to the reaction chamber by means of the light hydrocarbon fraction which is heated in coil 19.

Vapors from the reaction chamber are removed through line 40 and valve 41 to line 5 and thence to fractionator 6. The liquid portion of reaction products containing catalyst in suspension is withdrawn through line 42 and valve 43 to vaporizing chamber 44 which is maintained at a substantially lower pressure than reaction chamber 24. The major portion of the material is vaporized at this point and passed through line 45 and valve 46 which joins with line 40 and is passed to the fractionator 6. As in the case of reaction chamber 24, a liquid level may be main-

tained in vaporizing chamber 44 in order to obtain additional benefit of the catalyst and to prevent the catalyst from separating and plugging the lines. A portion or all of the heated low boiling fraction from line 21 may be passed through line 23 and valve 23' to line 42 and valve 43 to supply additional heat and assist in vaporizing the oil in chamber 44. Residue containing catalyst in suspension is removed through line 47 and valve 48 to catalyst recovery system not shown. The catalyst is separated from the oil by filtering or other suitable means, and reactivated by treatment with an oxygen-containing gas at a temperature within the range of approximately 800-1500° F.

Cracking catalysts suitable for use in the present operation may comprise the so-called silica-alumina, silica-zirconia, silica-alumina-zirconia type catalyst which may be or may not contain small quantities of boron oxide or other agents to improve the catalytic activity thereof. Composites of this type are prepared by the separate or simultaneous precipitation of the component parts followed by washing and drying under such conditions that alkali metal ions are substantially removed. The catalyst is used in the form of a finely divided powder preferably approaching colloidal dimensions in order to obtain a high degree of catalytic surface and to prevent an undue amount of settling at various points in the equipment.

Other cracking catalysts may be used such as naturally-occurring earths or naturally occurring earths which have been treated with acid or other chemicals to increase their catalytic activity.

Still another type of catalyst comprises relatively inert carriers such as alumina, magnesia, titania, zinc oxide, etc., having deposited thereon relatively minor amounts of the oxides or sulfides of molybdenum, chromium, vanadium, etc. This type of catalyst may also be mixed in varying proportions with silica-alumina, silica-zirconia, etc., type of catalyst.

The catalytic agents mentioned for use in the present process are not necessarily equivalent in the reactions they promote or in the yield of desirable products obtainable. They vary considerably in catalytic activity and the optimum temperature and pressure conditions, for each catalyst is not necessarily the same.

The following example is given to illustrate the usefulness and practicability of the process, but should not be construed as limiting it to the exact conditions or catalysts used therein.

A Pennsylvania distillate boiling in the range of approximately 400-760° F. may be treated in the manner described in the foregoing specification wherein a light oil side cut of approximately kerosene boiling range is processed in the light oil coil and the residual portion is mixed with approximately 2% by weight of silica-alumina cracking catalyst powder for treatment in the heavy oil coil. The light oil fraction is heated to a temperature of approximately 975° F. under a pressure of approximately 500 pounds per square inch. The heavy oil fraction is heated to approximately 800° F. under a pressure of 200 pounds per square inch. The reaction chamber is maintained at a temperature of approximately 850-875° F. and a pressure of 175 pounds per square inch. Vaporous reaction products are removed to the fractionator and the liquid products containing catalyst in suspension are passed to the vaporizing chamber which is maintained

at a pressure of approximately 50 pounds per square inch. A total yield of gasoline amounting to 72% of the original charging stock may be obtained in this way. An additional quantity is obtainable by polymerization of the normally gaseous olefins contained in the gases.

I claim as my invention:

1. A hydrocarbon oil conversion process which comprises fractionating the charging oil together with cracked vapors formed in the process in a fractionating zone, removing from said zone a relatively heavy cracking stock and a lighter cracking stock, commingling a powdered cracking catalyst with the heavy stock and heating

15 the mixture to at least 500° F. in a heating zone, discharging the heated mixture into a reaction zone, thermally cracking said lighter stock in a second heating zone at higher temperature than that to which said mixture is heated in the first-named heating zone, discharging resultant heated products into the reaction zone and therein transferring heat from said products to said mixture, removing vapors from the reaction zone and supplying the same to the fractionating zone, and finally condensing the fractionated vapors.

2. A hydrocarbon oil conversion process which comprises fractionating the charging oil together with cracked vapors formed in the process in a fractionating zone, removing from said zone a relatively heavy cracking stock and a lighter cracking stock, commingling a powdered cracking catalyst with the heavy stock and heating

30 the mixture to at least 500° F. in a heating zone, discharging the heated mixture into a reaction zone, thermally cracking said lighter stock in a second heating zone at higher temperature than that to which said mixture is heated in the first-named heating zone, discharging resultant heated products into the reaction zone and therein transferring heat from said products to said mixture, removing vapors from the reaction zone and supplying the same to the fractionating zone, separately removing admixed unvaporized oil and catalyst from the reaction zone and reducing the pressure thereon to form additional vapors, supplying the latter to the fractionating zone, and finally condensing the fractionated vapors.

3. A hydrocarbon oil conversion process which comprises commingling a powdered cracking catalyst with a relatively heavy oil, introducing the resultant mixture to a reaction zone maintained under catalytic cracking conditions, simultaneously subjecting a lighter oil to thermal cracking at higher temperature than that maintained in the reaction zone, discharging resultant heated products into the reaction zone and therein transferring heat from said products to said mixture to supply heat for the catalytic cracking of said heavy oil, removing vapors from the reaction zone and fractionating and condensing the same, separately removing admixed unvaporized oil and catalyst from the reaction zone and introducing the same to a reduced pressure vaporizing zone, and discharging additional heated products from the thermal cracking step into said vaporizing zone to assist the vaporization of oil from catalyst therein.

4. The process as defined in claim 3 further characterized in that vapors evolved in the vaporizing zone are combined with the vapors from the reaction zone for fractionation and condensation therewith.

WILLIAM EDWARD LEMEN.
